UNITED STATES PATENT OFFICE.

FRED ALDRED, OF GLENCOE, ONTARIO, CANADA.

CHURN.

SPECIFICATION forming part of Letters Patent No. 238,017, dated February 22, 1881.

Application filed December 20, 1880. (Model.) Patented in Canada July 15, 1880.

To all whom it may concern:

Be it known that I, FRED ALDRED, of Glen-
coe, Province of Ontario, Dominion of Canada,
have invented a new and useful Improvement
5 in Churns, (for which I have received Letters
Patent in Canada, No. 11,498, dated July 15,
1880,) of which the following is a specification.

Figure 1 is a sectional side elevation of the
improvement. Fig. 2 is a sectional end ele-
10 vation. Fig. 3 is an end elevation.

Similar letters of reference indicate corre-
sponding parts.

The object of this invention is to furnish
churns so constructed that they can be easily
15 operated and will bring the butter in a very
short time.

A represents the churn-body, the bottom
and top of which are horizontal, the sides ver-
tical, and the ends semi-cylindrical in form.
20 In the middle part of the top of the churn-
body A is formed a large opening for con-
venience in putting in the milk and taking
out the butter, which opening is surrounded
25 by a flange, B, and is closed by a cover, C,
fitting into the space within the flanges B and
resting upon the top of the churn-body at the
sides of the opening. The cover C is pro-
20 vided with a knob or other handle, D, for con-
venience in removing and replacing the said
cover.

To the ends of the churn-body A, and above
its central line, are attached two sockets, E,
35 to receive the ends of the springs F. If de-
sired, the sockets E can be made in the form
of pairs of hooks to receive the end parts of
cross-pins N, attached to the ends of the
springs F. The latter construction is shown
40 in the drawings, and is preferred, as giving the
springs a greater freedom of movement. The
lower ends of the springs F are secured, by
bolts or other suitable means, to a frame or
platform, G, which rests upon the floor or
45 other suitable support, and may be secured to
the floor by hand-screws H or other conven-
ient means, to prevent it from moving when
the churn is being used.

The springs F are made S shape, as shown
in Fig. 1, the upper ends being so formed as
to correspond with the curves of the ends of
50 the churn-body A to give greater elasticity to
the springs, and to allow the churn-body to
have a longer swing.

To the upper parts of the ends of the churn-
body A are attached handles I, for conven-
55 ience in operating the churn.

In the inner surface of the sides of the
churn-body A, at the corners of the opening
in the top of the said churn-body, are formed
short vertical grooves J to receive the ends of
one or more cross-bars, K.

60

To the cross-bars K are attached parallel
bars or fingers L, which project to, or nearly
to, the bottom of the churn-body A, as shown
in Figs. 1 and 2.

If desired, the dashers K L may be made 65
in the form of perforated or slotted boards or
plates, in which case the grooves J may ex-
tend to, or nearly to, the bottom of the churn-
body A. The dashers K L are secured in
place by the cover C, or they may be perma-
70 nently attached to the churn-body; but I pre-
fer to make them removable for convenience
in cleaning the churn-body.

In using the churn the milk is poured in,
and the cover C is put on. The operator then 75
takes hold of one of the handles I, and moves
the churn-body A forward and back longi-
tudinally, which change of motion, in connec-
tion with the semi-cylindrical form of the ends
80 of the churn-body, causes the milk to rise and
fall or be thrown back toward the middle part
of the churn - body, and the dashers K L,
through the openings of which the milk has
to pass, throw the milk into violent agitation
85 and bring the butter in a very short time. 85
When the churning has been finished and the
butter taken out, the butter-milk is drawn
out through an aperture in the lower part of
the side of the churn-body A, which aperture
90 is closed by a plug, M, a faucet, or other suit-
able means.

Having thus fully described my invention,
I claim as new, and desire to secure by Let-
ters Patent—

1. In a swinging churn, the supporting- 95
springs F, made in S shape, and attached to
the ends of the churn above the central line,
substantially as herein shown and described,
whereby the churn-body is supported and al-
lowed to vibrate, as set forth.

100

2. In a swinging churn, the combination,
with the churn-body A, of the S-shaped sup-
porting-springs F, provided with cross-pins N,
and the hook-sockets E, substantially as here-
in shown and described, whereby the churn- 105
body is allowed to vibrate freely, as set forth.

FRED ALDRED.
